SEALING-MACHINE.

1,4291,662.

Specification of Letters Patent.

Patented Jan. 14, 1919.

Application filed March 19, 1915. Serial No. 15,475.

To all whom it may concern:

Be it known that I, HARRY E. TOWNSEND, a citizen of the United States, residing at Brooklyn, in the county of Kings and State of New York, have invented new and useful Improvements in Sealing-Machines, of which the following is a specification.

This invention relates to sealing machines, and has particular reference to a combined exhausting and sealing machine in which the exhausting and sealing operations are performed in a single, unitary machine.

One object of the invention is to simplify the plant heretofore necessary in sealing mechanically containers under a vacuum, another object is to increase the mechanical efficiency of the plant, another object is to increase the speed of operation of the sealing mechanism, another object is to secure as high or higher a vacuum within the sealed container when the machine is driven at a high operative speed, and still other objects will appear in the following description and claims.

25 Referring to the drawings:

Figure 1 is a side elevation of the machine, partly in section; Fig. 2 is a front elevation, partly in section; Fig. 3 is an end elevation of the clutch mechanism taken in section on line 3—3 of Fig. 4; Fig. 4 is a sectional elevation of the clutch mechanism taken on the line of the driven shaft; Fig. 5 is a detail showing the operation of the clutch bolt; Fig. 6 is a sectional elevation showing the connections of sealing and exhausting chambers; Fig. 7 is a detail showing the operation of the sealing dies; Fig. 8 is a sectional elevation showing the valve mechanism; and Fig. 9 is a rear elevation of a power cam and follower taken on the line 9—9 of Fig. 1.

The present machine is designed primarily to apply metallic caps or closures to glass containers, after the air has been withdrawn from the container. The caps are preferably sealed mechanically to the glass container, so that the seal may be maintained without the help of atmospheric pressure. The sealing under vacuum of glass containers in this manner is a recent development and is a great advance in the art of packaging foods and the like.

In machines heretofore used for this purpose, means are employed to seal mechanically the closure to the glass container, and this means is suitably operated by power ap-

plied to each sealing machine for the purpose. In order to seal the containers under a vacuum it has further been necessary to connect each machine to a suitable air pump to exhaust the air from the container before it is sealed, a common arrangement being to have several sealing machines connected to a single exhausting air pump or air line.

With goods kept under vacuum, it is of great importance that the package be sealed under the highest attainable vacuum; many kinds of goods will not keep indefinitely unless sealed in a vacuum of not less than 26 or 27 inches, and an even higher vacuum is greatly to be desired. For this reason the arrangements described above are often found ineffective. The tendency of the packer to connect too many sealing machines with an air pump results in the packing being done under too low a vacuum, and many carloads of goods may be packed before it is discovered the goods will keep but a short time owing to the overloading of the air pump. This trouble may also appear where there is but a single sealing machine and an exhausting pump connected with it. In this instance, the pump and the sealing machine having independent power connections, usually belting or electric motors, the packer is inclined to speed up the sealing machine to increase production, while the pump is being driven at its ordinary speed. As in the former case, the goods will be packed under a low vacuum and their keeping qualities will be correspondingly impaired.

A single unitary structure in which is incorporated both a sealing mechanism and an exhausting pump is provided to eliminate these defects, and in this structure a driving means is provided that will always maintain the same relative speed of the sealing mechanism and the pump.

Mechanism constructed in accordance with the invention will accordingly provide for exhausting means combined with a sealing mechanism, the two united in a single structure and having a common driving means. While there are many ways of accomplishing this object, in the present embodiment of my invention, I employ a frame 10 comprising a base and an upright tubular portion incorporating a cylinder 11. Within the cylinder, as shown in Figs. 1 and 6, a trunk piston 12 is located, this piston be-

ing connected by a rod 13 to a crank 14 formed in the main shaft 15. These parts form the exhausting means, and as shown in Fig. 6, the upper part of the cylinder 11 5 communicates with channels or ports 16, 17 through which the air is withdrawn from the vacuum chamber represented at 18 whenever the piston 12 moves downward and the valve 19 puts the ports 16 and 17 in communication with each other.

This particular mechanism is adapted by a single downward stroke of the piston to exhaust the air from the vacuum chamber and the arrangement shown has several important advantages. The downward movement of the piston is harmonic—the piston starting slowly and accelerating until it has reached midstroke and then decreasing in speed. The slow initial movement prevents such a rapid exhaustion of air from the vacuum chamber as to cause the contents of the container to be sucked out; and the slow terminating movement occurs when the air behind the piston is most rarified and the load upon the piston is approaching its maximum, during which time the leverage of the crank is increasing so that the load upon the main shaft is comparatively uniform and the machine is more easily driven. By using a trunk piston, the size of the pump is not excessive, and it permits the pump cylinder and frame to be combined in a simple and compact structure of the most convenient height for supporting the vacuum chambers.

The sealing die mechanism, in the present illustration of my invention comprises a pair of annular dies 21 and 22, best shown in Figs. 6 and 7. The lower die 21 is adjustably supported in the vacuum chamber 18 and the upper die is adjustably mounted in a plunger 23 adapted to reciprocate in a bracket 24 bolted to the frame 10. As shown in Fig. 1, the plunger 23 is connected by a link 25 to a lever 26 fulcrumed at 27 to the bracket 24. The lever is connected through a compression spring 28 to a rod 29 which carries at its lower end a roll 30 engaging a cam 31 keyed to the main shaft 15, as shown in Fig. 9. The groove in cam 31 is so formed as to cause the rod 29 to move upward at a certain point in the rotation of the main shaft 15, this upward movement operating through spring 28 to depress the plunger 23 and cause the die 22 to move downward against the abutting die 21. As shown in Fig. 7, this closing of the two dies compresses the beading formed on the rim of the closure *a* and the gasket material *b* is forced laterally from the beading against the wall *c* of the glass container, thus sealing the closure *a* to the container in the well known manner.

The use of annular dies is of importance as it decreases the dead space in the vacuum

chamber. When sectional jaw dies are used, working spaces must be provided for their movement in expanding and contracting upon the closure beading, and this working space is relatively so great that a high vacuum could not be attained in a machine of the character disclosed, which has but a fixed and limited piston displacement for each operation.

Both the exhausting means and the sealing dies and mechanism are driven by the same shaft 15, so that it is impossible to speed up unduly the sealing die mechanism relatively to the exhausting means. The shaft 15 may be driven either continuously or intermittently, its operation being controlled by a pedal 33 pivoted to the frame 10 at 34 and provided with a clutch trip 35 adapted to engage a clutch bolt 36 which slides in the driven member 37 of a clutch. A spring 38 tends normally to move the bolt outward to engage the lugs 39, 39 on the driver member 40 of the clutch, and the clutch trip when elevated prevents the engagement of the clutch bolt and the lugs. The driver member is mounted loosely upon shaft 15 and is provided with a gear periphery which is driven by a spur gear 43 mounted upon a shaft 44 carrying a suitable belt pulley 45 through which power may be applied to the machine. The pedal is normally held upward by a spring 46. The clutch mechanism operates as a one-revolution clutch, the shaft 15 being rotated one revolution each time the pedal is depressed.

By means of this clutch, the machine may be operated intermittently as desired and at a rate corresponding with the delivery of the containers to the machine. As the machine consumes almost as much power in running idle as when exhausting and sealing containers, the clutch arrangement saves considerable power and also undue wear of the machine. It has a further advantage that when a glass container is broken during sealing, the machine can be stopped before the contents of the container are sucked into the pump.

It will be noticed that when the piston and crank reach their lowest position, the atmospheric pressure upon the under side of the piston is at a maximum and tends to drive the piston upward. When the crank passes the lower dead center the pressure upon the piston works with the driving gear rather than against it and unless means are provided to prevent it, the piston would tend to race upward, pulling the crank with it, thereby causing a chattering of the clutch and backslashing of the gears 40, 43. This backlash is prevented by a suitable port adapted to relieve the pressure upon the piston as the crank passes the lower dead center and after the container within the vacuum chamber has been

sealed, or the valve 19 closed. In the present instance this relief port is formed at 48 in the wall of the cylinder 11, and is so positioned with respect to the piston that 5 it is uncovered by the latter at the extreme end of the downward stroke, whereby air is admitted to the cylinder behind the piston and the pressure is relieved.

The mechanism described above is not 10 enough in itself to give the most effective results, for as already pointed out, it is of great importance to get the highest possible vacuum in the sealed container. In such a unitary structure the vacuum V will be in 15 accordance with the formula

$$V \text{ equals } \frac{a + b}{a + b + c} \text{ times } P$$

where a is the cubic capacity of the vacuum 20 chamber and residual space in container, b the cubic capacity of the ducts between the vacuum chamber and the cylinder of the pump, c the cubic capacity of the exhaust 25 ing cylinder, and P the barometer pressure.

It is obvious that the values of a and b must be made as small as possible with relation to the size of the pump cylinder.

In the construction shown, therefore, the 30 vacuum chamber 18 is located as close as possible to the cylinder 11 so that the ducts 16 and 17 have a small cubic capacity, and the chamber itself is of novel form and construction, as best shown in Fig. 6. A typical glass container is indicated by dotted 35 lines in the drawing at 50 and, as shown, is of a tapering cylindrical form. Containers, being made of pressed or blown glass, are manufactured more cheaply in this form as it facilitates the withdrawal of the glass 40 from the mold in its manufacture. The vacuum chamber is specially constructed to handle glass of this character and the principal part of the chamber is made up of a cup receiver. The chamber is formed of a 45 cylindrical sleeve 51 which cooperates with a foot-plate 52 and a sealing head 53 formed upon a bracket 24. Within the sleeve 51 is located a holder 54 adapted to reciprocate within the sleeve and to support the container 50.

Two of these sleeves and holders are shown slidably mounted in a turret 55 which is rotated intermittently by a shaft 56 so that each sleeve is successively brought into 55 registration with the sealing head 53. It will be noticed that the receiver, including the sleeve and holder, is substantially in the form of a cup, with its internal dimensions corresponding closely to the external 60 dimensions of the glass container, and that, in operation, the container is dropped into the receiver. This method of construction reduces the clearance or dead space between the container and the walls of the vacuum chamber to the minimum and is a large

factor in securing efficiency in this type of machine. The advantage of a cup receiver over a bell receiver is seen in that in the case of the bell receiver, the internal diameter of the bell would have to be something 70 greater than the largest diameter of the glass container or its cap, and the amount of dead space within the vacuum chamber would be so great that it would be impossible to secure a high vacuum.

The shaft 56 carrying the cup receivers is intermittently rotated by mechanism shown in Figs. 1 and 2. Main shaft 15 carries one member 60 of a Geneva train, and the other and driven member 61 is mounted on a stud 80 shaft 62 and has attached to it a bevel gear 63. The gear 63 meshes with gear 64 pinned to shaft 56, which is driven thereby. A bracket 65 is bolted to the frame 11 and forms a bearing for the shaft 56.

The foot-plate 52 is located below and in line with the sealing head 53 and is carried upon a rod 66 having a bearing in the bracket 65. The foot-plate and rod are reciprocated vertically by a cam 67 attached 90 to the main shaft 15 and operating upon a follower arm 68, crank 69 and connecting rod 70, as shown in full and dotted lines in Fig. 2.

To facilitate the insertion and withdrawal 95 of the containers, an ejector 71 is provided which is mounted in the bracket 65 and is in registration with the axis of the sleeve 51 when the latter is in its left hand position as viewed in Fig. 6. The ejector is 100 supported and reciprocated by a lever 72 pivoted to the frame at 73, having a pin and slot connection with rod 66 and coupled to the ejector by link 74.

By positioning the turret with vacuum 105 chambers and sealing mechanism on one side of the frame and the actuating devices for the sealing mechanism including rod 29 on the opposite side of the frame, as best shown in Fig. 1, a simple lever 26 is all that is required to give the pressure necessary for sealing, the machine can be built more cheaply and be driven with less power. A further advantage is that the actuating mechanism for the sealing devices may be 110 mounted upon the main shaft on one side of the crank, while the mechanism for the turret and vacuum chambers may be located upon the other side, making all the moving parts more accessible and giving a uniform 115 distribution of load upon the main shaft.

In operation, the ejector and the foot-plate move upward simultaneously while the turret 55 is momentarily at rest. As viewed in Fig. 6, the ejector raises the holder 54 allowing the sealed container to be easily withdrawn and an unsealed container inserted in its place; at the same time the foot-plate 52 raises the sleeve 51 into contact with the sealing head 53, hermetic joints being 120 125 130 135 140 145 150 155 160 165 170 175 180

formed by the gaskets 75 and 76. The vacuum chamber is thus formed and held sealed while the plunger 23 descends to effect the sealing operation upon the container, as previously described. The ejector and foot-plate then move downward until they are clear of the sleeves 51, whereupon the turret is rotated the necessary distance to repeat the operation.

10 I claim:

1. In a vacuum sealing machine, a vacuum chamber, opposed dies located within the chamber, actuating mechanism for the dies, a pump adapted to exhaust the air from said chamber, and a driving means common to the die actuating mechanism and the pump, and adapted to operate said pump and mechanism in sequence.
2. In a vacuum sealing machine, a vacuum chamber, opposed dies located within the chamber, actuating mechanism for the dies, a pump adapted to exhaust the air from said chamber, a driving means common to the die actuating mechanism and the pump, and adapted to operate said pump and mechanism in sequence, a clutch controlling the operation of the driving means, and a pedal for tripping the clutch.
3. In a vacuum sealing machine, a vacuum chamber, sealing mechanism located within the chamber, a pump adapted to exhaust the air from said chamber, a driving means common to the sealing mechanism and the pump, and adapted to operate said pump and mechanism in sequence, a clutch for controlling the operation of the driving means, and a device for tripping the clutch.
4. In a vacuum sealing machine, a vacuum chamber, sealing mechanism including annular dies located within the chamber, a pump adapted to exhaust the air from said chamber, and a driving means common to the sealing mechanism and the pump and adapted to operate said pump and sealing mechanism in sequence.
5. In a vacuum sealing machine, a vacuum chamber, sealing mechanism including annular dies located within the chamber, a pump adapted to exhaust the air from said chamber, a driving means common to the sealing mechanism and the pump and adapted to operate said pump and sealing mechanism in sequence, a clutch controlling the operation of the driving means, and a device for tripping the clutch.
6. In a vacuum sealing machine, a vacuum chamber, sealing mechanism located within the chamber, a piston pump adapted to exhaust the air from said chamber by a single piston stroke, and a driving means common to the sealing mechanism and the pump, and adapted to operate said pump and sealing mechanism in sequence.
7. In a vacuum sealing machine, a vacuum chamber, sealing mechanism located within

the chamber, a piston pump adapted to exhaust the air from said chamber by a single piston stroke, a driving means common to the sealing mechanism and the pump, and a relief port for the pump to prevent backlash 70 of the driving means.

8. In a vacuum sealing machine, a vacuum chamber, sealing mechanism located within the chamber, a crank-driven piston pump adapted to exhaust the air from said chamber by a single piston stroke, and a driving means common to the sealing mechanism and the pump, and adapted to operate said pump and sealing mechanism in sequence.

9. In a vacuum sealing machine, a vacuum chamber, sealing mechanism located within the chamber, a pump adapted to exhaust the air from said chamber, a driving means including a clutch and gears common to the sealing mechanism and the pump, and a relief port for the pump to prevent chattering 85 and backlash of the clutch and gears.

10. In a vacuum sealing machine, a vacuum chamber, sealing mechanism located within the chamber, a pump adapted to exhaust the air from said chamber, a driving means common to the sealing mechanism and the pump, and a relief port for the pump adapted to be opened after the operation of the sealing 90 mechanism whereby backlash of the driving 95 means is prevented.

11. In a vacuum sealing machine, a cup receiver and a sealing head comprising a vacuum chamber, sealing mechanism located within the chamber, a pump adapted to exhaust the air from said chamber, and a driving means common to the sealing mechanism and the pump, and adapted to operate said pump and sealing mechanism in sequence.

12. In a vacuum sealing machine, a cup 105 receiver and a sealing head comprising a vacuum chamber, sealing mechanism including annular dies located within the chamber, a pump adapted to exhaust the air from said chamber, and a driving means 110 common to the sealing mechanism and the pump, and adapted to operate said pump and sealing mechanism in sequence.

13. In a vacuum sealing machine, a cup 115 receiver and a sealing head comprising a vacuum chamber, sealing mechanism located within the chamber, a piston pump adapted to exhaust the air from said chamber by a single piston stroke, and a driving means 120 common to the sealing mechanism and the pump, and adapted to operate said pump and sealing mechanism in sequence.

14. In a vacuum sealing machine, a cup 125 receiver comprising a sleeve open at its upper end, a holder located within the sleeve and adapted to support a container lowered into the receiver, and an ejector adapted to reciprocate the holder within the sleeve and to be withdrawn clear from said sleeve.

15. In a vacuum sealing machine, a cup 130

- receiver comprising a sleeve open at its upper end, a holder located within the sleeve and adapted to support a container lowered into the receiver, an ejector adapted to reciprocate the holder within the sleeve, and a foot-plate for closing the lower end of the sleeve, the said ejector and foot-plate being adapted to operate alternately.
16. In a vacuum sealing machine, a rotary turret and a plurality of cup receivers carried by the turret, the said receivers each including a sleeve vertically slideable in the turret, and a holder located inside the sleeve and vertically slideable therein.
- 15 17. In a vacuum sealing machine, a rotary turret and a plurality of cup receivers carried by the turret, the said receivers each including a sleeve vertically slideable in the turret, and a holder located inside the sleeve and vertically slideable therein in combination with a sealing head and a foot-plate adapted to coöperate with the cup receiver to form a vacuum chamber.
18. In a vacuum sealing machine, a rotary turret, a plurality of cup receivers carried by the turret, the said receivers each including a sleeve and a holder located within the sleeve, an ejector relatively stationary to the turret and adapted to act upon the holders in succession, a foot-plate relatively stationary to the turret and adapted to coact with the sleeves in succession, and means to cause simultaneous operation of the said ejector and foot-plate.
- 35 19. In a vacuum sealing machine, a sealing head, a rotary turret below the sealing head, sleeves carried by the turret and adapted to register with the sealing head, a foot-plate below the turret and in registration with the sealing head, the said foot-plate being adapted to form a vacuum chamber by contacting with a sleeve and raising it into contact with the sealing head.
20. In a vacuum sealing machine, an intermittently rotating turret, a pair of cup receivers mounted in the turret, a sealing head and foot-plate positioned relatively to the turret to register with one of the receivers, and an ejector adapted to coöperate 50 simultaneously with the other receiver.
21. In a vacuum sealing machine, a frame comprising a base adapted to support a main power shaft, the frame having an upright tubular portion formed at its upper end into a pump cylinder, and brackets attached to the upright portion of the frame and adapted to support a vacuum chamber and sealing mechanism.
- 55 22. In a vacuum sealing machine, a combined vertical frame and pump cylinder, a vacuum chamber and sealing mechanism positioned on one side of the frame, and means to actuate the sealing mechanism located upon the opposite side of the frame.
- 55 23. In a vacuum sealing machine, a vacu-
- um chamber, an exhaust pump, sealing mechanism, a main shaft equipped with a crank adapted to operate the pump, actuating devices for the vacuum chamber coupled with and driven from the main shaft at one side of the crank, actuating devices for the sealing mechanism coupled with and driven from the main shaft at the other side of the crank, a gear drive for the main shaft, a clutch interposed between the gear drive and the main shaft, and a trip for the clutch.
24. In a vacuum sealing machine, a sealing head positioned over a sealing station, a package carrier adapted to move and position a package beneath said sealing head, and means for causing said sealing head to cover said package carrier to hermetically inclose said package when positioned at the sealing station, in combination with a piston pump adapted to exhaust the air from around said package by a single piston stroke, and driving means operatively connected with said sealing head and said pump whereby said head and said pump are operated in sequence.
25. In a vacuum sealing machine, a sealing head, a package carrier, means to move said carrier to position a package therein beneath said sealing head, and means to cause a relative vertical movement between said carrier and said head whereby a closed chamber is provided around said package, in combination with a vacuum pump adapted to exhaust air from said chamber by a single stroke, and driving mechanism operatively connected with said vacuum pump and said sealing head to operate said pump when said head has engaged the package carrier to form a closed chamber.
26. In a vacuum sealing machine a packing carrier, a closure-head coöperative with said package carrier to form a closed chamber around a package in said carrier, a sealing anvil having a vertical movement through the closure head to seat a cap on a package within said carrier; means for positioning said package carrier beneath said closure; in combination with means for exhausting the air from around said package when said closure is seated over said package carrier, the movement of said package carrier, the closing of said chamber, the exhausting of air from said chamber, and the seating of said cap occurring in sequence.
27. In a vacuum machine the combination of a package carrier, a head adapted to coöperate with said package carrier to form a closed chamber around the package within said carrier, means for intermittently positioning the package carrier beneath said head, a sealing anvil having a movement at substantially right angles to the travel of said package carrier when said package carrier is being moved to position beneath said head, said sealing anvil being adapted to

6
seat a suitable cap on a suitable package within said package carrier when said carrier is in engagement with said head, and a single-stroke exhausting mechanism for exhausting the air from around said package prior to the seating of the cap thereon.

28. In a vacuum machine a pocket adapted to receive and transport a suitable package adapted to be sealed, means for positioning said pocket beneath a closure head, devices 10 for causing a relative movement between

said closure head and said pocket whereby said head closes the upper end of said pocket, an anvil operative vertically through said head to seat a suitable cap on a suitable package within said pocket when said head is in engagement with said pocket, and a piston pump adapted to exhaust the air from said pocket by a single piston stroke, and driving mechanism whereby said pump and 15 said anvil are operated in sequence.

HARRY E. TOWNSEND.
